CLAIM

The ornamental design for a tipping truck, as shown and described.

DESCRIPTION

FIG. 1 is a front view of the tipping truck showing my new design;

FIG. 2 is a rear view thereof;

FIG. 3 is a top plan view thereof;

FIG. 4 is an underneath plan view thereof;

FIG. 5 is a view of one side thereof; and,

FIG. 6 is a view of the other side thereof.

The broken line showing in FIG. 4 is included for the purpose of illustrating environment and forms no part of the claimed design.

1 Claim, 5 Drawing Sheets

FIG. 2**FIG. 1**FIG. 3

FIG. 4**FIG. 5**

FIG. 6
